CLAIM

The ornamental design for a dry shaver, as shown and
described.

DESCRIPTION

FIG. 1 is a front, top, right side perspective view showing
our new design with the roller-shutter portion re-
tracted;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof; and,

FIG. 8 is a front, top, right side perspective view showing
our new design with the roller-shutter extended to
cover the shaving head portion.
